DIATHERMY ELECTRODE

Godfrey P. Goode, Park Hills, Ky., assignor to Ritter Company, Inc., Rochester, N.Y., a corporation of Delaware

Filed Sept. 21, 1964, Ser. No. 81,823

Term of patent 14 years

(Cl. D83—1)

FIG. 3

FIG. 1

FIG. 2

FIG. 4

FIG. 1 is a side elevation of a diathermy electrode showing my new design;

FIG. 2 is an end view thereof;

FIG. 3 is a bottom plan view thereof;

FIG. 4 is a top plan view in an extended position.

The essential features of my design reside in the solid line portions.

I claim:

The ornamental design of a diathermy electrode, substantially as shown and described.
